REPLACEMENT OVEN UNITS

Joseph J. Jasionowski, Niles, Ill., assignor to Ferro Corporation, a corporation of Ohio

Filed May 9, 1963, Ser. No. 279,278

3 Claims. (Cl. 219—402)

This invention relates in general to electric heating units, and more particularly to replacement bake and broil heating units and means for mounting them in an oven.

Several ways of installing bake and broil units in a range oven are known in the prior art. For example, it is known to provide the rear oven wall with central openings, one located adjacent the top of the wall for the broil unit, and another located at the bottom of the wall for the bake unit. In other ovens it is conventional to provide an opening adjacent one side of the rear oven wall at the top and the bottom to mount the broil and bake units for swiveling movement with respect to the openings. It is also known to provide openings in the oven rear wall on both sides at the top and the bottom to accommodate generally U-shaped broil and bake units. The general purpose of the present invention is to provide replacement oven units which are capable of being mounted in each of the oven constructions set forth above.

An object of the present invention is the provision of mounting means for a replacement oven unit which is capable of securing the oven unit to an oven wall regardless of the mounting openings already present in the wall.

Another object of the invention is to provide a new and improved mounting means for a heating unit which will allow the unit to be installed or replaced from the front of the oven.

Still another object of the present invention is to provide mounting means for replacement oven units which will allow the units to be moved in the oven so that the oven walls may be easily cleaned.

A further object of the present invention is to provide mounting means for a replacement oven unit which present smooth planar surfaces that are easy to clean.

A still further object of the invention is to provide a replacement oven unit which is simple in construction, efficient in operation, well adapted for its intended purposes, and relatively inexpensive to manufacture and maintain.

Other objects and advantages of the invention will become readily apparent from the following detailed description taken in connection with the accompanying drawings, in which:

FIGURE 1 is a perspective view of an oven broken away showing a heating unit mounted in accordance with the present invention;

FIGURE 2 is a view taken substantially as shown along line 2—2 of FIGURE 1;

FIGURE 3 is a view similar to FIGURE 2 showing the heating unit housing in a pivoted position;

FIGURE 4 is a sectional view taken substantially as shown along line 4—4 of FIGURE 2;

FIGURE 5 is a front elevational view of a mounting bracket used in the present invention;

FIGURE 6 is a front elevational view of another mounting bracket used in the present invention;

FIGURE 7 is a sectional view taken substantially as shown along line 7—7 of FIGURE 5;

FIGURE 8 is a sectional view taken substantially as shown along line 8—8 of FIGURE 5;

FIGURE 9 is a perspective view of an oven broken away showing a modified form of a heating unit mounting;

2

FIGURE 10 is a front elevational view of an oven rear wall using the heating unit mounting means shown in FIGURE 9, with the heating element broken away for clarity;

5 FIGURE 11 is a front elevational view of an extension mounting bracket; and

FIGURE 12 is a sectional view taken substantially as shown along line 12—12 of FIGURE 10.

While this invention is susceptible of embodiment in many different forms, there is shown in the drawings and will herein be described in detail only specific embodiments, with the understanding that the present disclosure is to be considered as an exemplification of the principles of the invention and is not intended to limit the invention to the embodiments illustrated. The scope of the invention will be pointed out in the appended claims.

Referring now to the drawings, wherein like reference characters designate like or corresponding parts throughout several views, reference numeral 20 is used in FIGURE 1 to indicate the oven in its entirety. Oven 20 includes a top wall 21, side walls 22 and 23, a rear wall 24, and a bottom wall 25. Oven 20 is of the type having two central openings in the rear wall 24 adjacent the top and bottom walls, respectively, and is shown with a bake unit 26 secured to rear wall 24 by mounting means 27. It should be understood that the forward end of unit 26 is supported by any suitable means such as by legs 28.

The aforementioned lower central opening in wall 24 is shown at 29 in FIGURE 4. Mounting means 27 includes a substantially rectangular bracket 30 (FIGURE 6) that is sufficiently large to overlie variously sized openings 29 found in different ovens. Bracket 30 is provided with a pair of central vertically spaced apart knock-out holes 31 that are adapted to receive toggle bolts, not shown, as is disclosed in co-pending application Serial No. 219,472, filed August 27, 1962. As is set forth in detail in that application, holes 31 are selectively usable, depending upon the position of the bracket relative to the wall aperture. If the wall aperture is too narrow to allow a toggle bolt to pass therethrough, or is too wide to allow firm gripping action by the toggle bolt, additional knock-out holes 32 adjacent the sides of bracket 30 are used to secure the bracket to the oven wall. As is seen in FIGURE 4 metal screws 33 extend through the openings formed at 32 and engage oven wall 24 adjacent the sides of opening 29. Bracket 30 is provided with an additional pair of laterally spaced apart openings 34 that are adapted to receive therethrough the end portions of leads 35 and 36 that are connected to a source of electrical energy, not shown. Openings 34 are provided with rolled over beads 37 and 38 to prevent the fraying of leads 35 and 36. Bracket 30 further includes spaced apart longitudinal knock-out holes 39 for the insertion of a supplemental heating element if desired (not shown) and a pair of spaced apart holes 40, the purpose of which will hereinafter become apparent.

A modified form of bracket 30' is illustrated in FIGURE 5 and is adapted to be used in the aforescribed type of ovens having openings adjacent the top and bottom of the rear oven wall on one or both sides of the wall. The central portion of bracket 30' is substantially identical with bracket 30, and common elements have been indicated with primed numerals in FIGURES 5, 7 and 8. Bracket 30' is substantially longer than bracket 30 and is provided at its outermost ends with horizontally disposed longitudinal slots 41. Adjustable extension members 42 are provided at each end of bracket 30' to enable the bracket to accommodate ovens having variously sized widths. As is best seen in FIGURE 8, bracket 30' is substantially U-shaped in cross section having legs 30a and 30b. Extension members 42 are also U-shaped in cross section having leg members 42a and 42b which are

telescopically received within legs 30a and 30b and ride therealong. Each extension member 42 is provided with a plurality of laterally spaced openings 43 which are adapted to be selectively aligned with the corresponding slot 41 at the desired laterally adjusted position. Screws 44 impale slots 41 and holes 43 at the desired position, and nuts 45 secure the respective parts in place. Each extension member 42 is provided with at least two laterally spaced rows of knock-out openings 46. Knock-out openings 46 are also vertically spaced so as to be capable of being positioned over any mounting holes which may be present in the oven rear wall. It will be readily understood that if it is not possible to align an opening 46 with an existing oven wall hole, toggle bolts, not shown, may be passed through an opening 46 and into the adjacent rear wall oven aperture to secure the bracket in position. In FIGURES 9 and 10, bracket 30' and extension brackets 42 are shown as used in an oven 20' having openings at both sides of the top and the bottom of the rear oven wall indicated by reference numerals 47-50. As was discussed above, it should also be kept in mind that this type of mounting is also suitable for a heating element having side terminations. It will be noted that bracket 30' and extensions 42 cooperate to form an effective shielding means for leads 35 and 36.

Referring now to FIGURES 2-4, it will be noted that the end portions 51 and 52 of the heating element terminate in a housing indicated generally by reference numeral 53. Housing 53 includes a first U-shaped member having a base 54 with apertures 55 aligned with bracket apertures 34 to admit the ends of leads 35 and 36 into the interior of the housing. It should also be understood that base 54 is provided with a suitable central opening, not shown, that is aligned with openings 31 to accommodate the toggle bolt, not shown. The first U-shaped member also includes apertured sides 56 which receive therethrough the end portions 51 and 52 of the heating unit. Bosses 57 surround the side member apertures, and extend outwardly from sides 56 a sufficient distance to enable them to be crimped into secure gripping engagement with heating unit end portions 51 and 52 so as to fixedly mount the heating unit relative to the housing. Base 54 is secured to a flexible strip of metallic material 58 as by rivets, not shown, to provide hinge means for the heating elements as will hereinafter become more fully apparent. The upper end of strip 58 is secured to bracket 30 as by screws 59, which pass through aforementioned holes 40, and the lower end is free of bracket 30 to be swingable relative thereto.

Suitable means, such as plates 60 and screws 61, are provided to electrically connect leads 35 and 36 with ends 51 and 52 of the heating element. Tubes 63 of insulating material surround these connections.

Housing 53 further includes a second U-shaped member having a base 64 abutting the ends of sides 56, and legs 65 positioned on the top and bottom of sides 56. The upper leg 65 is provided with an inwardly bent downwardly struck portion 66 which is engageable with an upwardly open groove 67 in each side 56 to provide means for locking the second U-shaped member on the first U-shaped member. It will be readily understood that

the second U-shaped member may be easily removed by merely spreading legs 65, and when it is replaced it will snap into place due to the cooperation of portions 66 and grooves 67.

Referring now to FIGURE 12, where both a broil unit 68 and a bake unit 26 are shown, it should be noted that the mounting 69 for the broil unit 68 is substantially identical to the mounting 27 for the bake unit 26, except that the parts are reversed to allow broil unit 68 to pivot downward with respect to the oven top surface 21. A magnet 70 is provided at the outer end of broil unit 68 to secure it to surface 21.

From the foregoing it should be apparent that what has been provided are replacement oven units which are capable of being installed in a wide variety of presently available ovens. The mountings for the units present substantially flat surfaces which are simple to clean, and the units themselves are movable so as to allow the oven surfaces to be cleaned. The heating units and their mountings are readily accessible from the front of the oven for proper maintenance and repair. Thus it will be appreciated that all of the objects of the invention have been fully achieved.

I claim:

1. Means for securing an electrical heating unit to an apertured wall of an oven comprising: a bracket having a flat face and being of sufficient size to cover the aperture in said wall, means for securing the bracket in position overlying said aperture and with said face closely spaced from said wall, a small compact housing having a removable cover, said housing having dimensions in a plane parallel to the plane of said wall less than the corresponding dimensions of the face of the bracket, an electrical connector mounted in said housing, a sheathed electrical heating unit having terminals terminating in said housing and secured to said connector therewithin, electrical leads extending through an aperture in said wall and through openings in said bracket, with said leads terminating in said housing and being secured to said connector, and means hingedly securing said housing to said bracket.

2. Apparatus of the character described in claim 1 in which said bracket is generally rectangular in shape and is provided with a short wall extending from each side thereof normal to the plane of the face to space said face from the apertured wall.

3. Apparatus of the character described in claim 2 including a pair of channel-shaped extension members extensibly secured to opposite sides of the bracket with the legs of the extension members extending in the same direction and for approximately the same distance as the walls of the bracket, said extension members being adapted to overlie and protect the electrical leads.
